UNITED STATES PATENT OFFICE.

JAMES G. NOLEN AND JOHN E. SHEPHERD, OF CHICAGO, ILLINOIS.

FIRE-PROTECTION SIGNAL SYSTEM.

No. 802,875.

Specification of Letters Patent.

Patented Oct. 24, 1905.

Application filed March 20, 1905. Serial No. 250,957.

To all whom it may concern:

Be it known that we, JAMES G. NOLEN and JOHN E. SHEPHERD, of Chicago, in the county of Cook and State of Illinois, have invented 5 certain new and useful Improvements in Fire-Protection Signal Systems; and we hereby declare that the following is a full, clear, and exact description thereof, reference being had to the accompanying drawings, which form 10 part of this specification.

Our invention relates to improvements in fire-protection signal systems, and has for its general object to provide, in association with an automatic fire-extinguisher system, a signaling system whereby supervision over the condition of devices of the sprinkler system may be maintained.

One of the objects of our invention is to provide, in conjunction with a fluid-receptacle of a fire-extinguisher system, means for supervising the condition of pressure, liquid-level, and temperature therein to guard against the prevalence of abnormal conditions which will injure the effectiveness of the 25 sprinkler system when in operation.

A further object of our invention is to so provide and arrange these devices that those in authority at the supervising station may note the signals transmitted, whether the condition in the receptacle being supervised is 30 such as indicates local trouble only or such as indicates the conditions naturally consequent upon the action of the sprinkler system in extinguishing a fire.

35 Other and further objects of our invention will hereinafter become apparent.

Referring now to the drawings, Figure 1 is a diagrammatic view showing a typical application of our invention. Fig. 2 is a diagrammatic view of a signal-transmitter. Fig. 3 is 40 a perspective view of a detail of said transmitter as diagrammatically shown. Fig. 4 is a detail of a pressure-indicator, such as is well adapted for the practice of our invention.

45 Throughout the drawings like numerals and letters of reference refer always to like parts.

In certain of its features our invention is particularly applicable to the supervision of elements of a fire-extinguisher system wherein 50 a certain pressure should be maintained at a certain liquid-level step to secure the proper action of the sprinkler system. Such conditions are present, for example, in the risers of dry-pipe extinguisher systems or in pressure-tanks, which are commonly employed in

extinguisher systems, as will be well understood by those skilled in the art.

For purposes of illustration we have shown our invention as applied to the supervision of the riser of a dry-pipe extinguisher system, 60 wherein—

A represents the riser, and B a differential valve, below which the water or other extinguishing liquid should be maintained at a constant level while the sprinkler system is 65 in passive condition by the pressure of air filling the piping above the variable pressure-valve. The maintenance of such conditions in a dry-pipe system is often of the gravest importance, as such systems are frequently 70 used where the area to be protected by a sprinkler is apt to be at such a low temperature that water standing in the pipe would freeze, thereby disabling the entire sprinkler system in case of fire.

75 For the complete supervision of the conditions in the riser or other receptacle we provide devices operating in response to undue variations in the conditions to be maintained in association with a suitable alarm or signaling system.

Specifically, devices typical of those which may be employed are the water-level indicator C, the pressure-indicator D, and the temperature-indicator E. Preferably 80 these devices are arranged to show the condition immediately above the variable pressure-valve or other point at which the water-level should be maintained, and they may conveniently be constructed and arranged as follows:

a indicates a pipe tapping the riser A at a 85 suitable point above the variable pressure-valve B, said pipe communicating with a chamber c, wherein is suspended a float-ball c', pivoted, as at c'', and provided with a lever part c'', engaging the inner end of a lever c', fulcrumed in a diaphragm c'', closing an opening in the wall of the chamber c, said lever being at its outer end associated with suitable circuit-controlling devices to be described. At 90

its outer end the chamber c opens into the pressure-indicator D, which preferably comprises the bowed hollow spring member d, which under pressure created in the interior thereof tends to straighten or unbend. The end of said tube is connected by a link d' with 100 a lever d'' in such manner as to properly move said lever, the parts being herein shown and arranged in such manner that as the spring-coils tighten under the reduction of pressure upon the water within its hollow interior the 105

longer arm of the lever d^2 is raised. d^3 indicates a receptacle containing mercury, to which I will refer as a mercury contact. d^4 indicates a contact-point carried by the lever d^2 and preferably under the pressure conditions normally prevailing in the riser A dips into the mercury contact d^3 . When the loop of the spring-tube d is contracted by the effect of decreased pressure, the contact d^4 is raised 10 out of contact with the mercury contact d^3 . The temperature-indicator E may be of suitable character to afford an indication of the temperature of the fluid or liquid within the receptacle just above the valve B and is shown 15 as comprising an ordinary thermometer E, having a wire led into a mercury bulb, a contact-point at a degree approximating freezing-point, and another contact-point at a degree approximating boiling. The exact location of these contact-points may be varied 20 to suit the requirements of the fire-underwriters' board or other officials. It will be apparent, however, that between freezing and boiling point, or, in other words, under normal 25 conditions, the mercury closes electrical connection or circuit between the two lower contacts. In the supervision of these indicating devices we preferably provide a suitable signal-transmitting device for each of the 30 indicating devices, said transmitting devices being preferably connected with suitable central-station signal-receiving apparatus, preferably receiving signals from all of said transmitters in common, so that in case of receipt 35 of signals from more than one transmitter the order of their transmission may be readily noted.

A transmitting device suitable for the practice of our invention is diagrammatically illustrated in Figs. 2 and 3, and in said views F indicates the transmitter in general, comprising a spring motor-driven train f , arranged to simultaneously rotate two number-wheels f' and f'' , each having a series of circuit-breaking teeth and a raised peripheral circuit-breaking portion disposed in position corresponding in time of operation with the toothed portion of the opposite wheel. An electro-responsive device G, preferably an electro-magnet, is arranged to control the movements of the train f , having an armature g , mounted upon a lever g' , provided with two fingers g^2 and g^3 , having inturned ends adapted to coact with notches f^4 f^5 , respectively, arranged at different elevations in an annular flange f^6 , carried by a wheel f^6 of the gear-train. The arrangement of parts is such, assuming the magnet-armature to be attracted and the fingers g^2 to be in engagement with 55 the notch f^4 , if the magnet be de-energized so that the armature-spring retracts, the armature throwing the finger g^3 against the inner side of the flange f^6 , the clock-train operates until the notch f^5 is engaged by the finger g^3 60 after a half-revolution of the wheel f^6 . Dur-

ing this time the number-wheels f' f'' each make a full revolution. If now the armature g be again attracted by its magnet G, the wheel f^6 is again released for a half-revolution, during which time the number-wheels again make 70 each a full revolution before the finger g^2 again engages the notch f^4 . While such a form of device is very convenient and has many advantages, we do not desire to be understood as limiting ourselves thereto in the 75 broader aspect of our invention; but we have shown said transmitter diagrammatically for purposes of full illustration. All of the transmitters may be alike, and we have therefore shown the three transmitters associated, respectively, with the pressure-indicator, the liquid-level indicator, and the temperature-indicator, as F' F'' F^3 .

In their wiring arrangements in general we prefer that the transmitters should be all alike, 85 and we will therefore describe the wiring connections of the transmitter F' and its electro-responsive devices G', it being understood that the other transmitters are similarly wound, except in matters hereinafter specifically mentioned.

From the central-station generator H extends a main-line wire 10, including the coils 11 of a relay I, and leading to the pen 11 of wheel f' of said box F' . Said pen is arranged 95 normally out of contact with its wheel and in contact with a coacting point 12. From the pen 11 the circuit branches into two parallel connections, one, which I will arbitrarily term the "main" branch, including the contact 12, wire 13, coils 14 and 15 of the balanced magnet G', and wire 16, which terminates at a juncture-point 17. The other branch, which I will arbitrarily term the "supervisory" branch, extends from said pen 11 by wire 18 100 to a pen 19 of the number-wheel f'' of the transmitter F' , likewise normally out of contact with its wheel, but in contact with a coacting contact member 20, connected by wire 21 with a coil 14' of the magnet G', the opposite end whereof is connected by wire 22 with the mercury contact d^3 of the pressure-indicator, the contact-point d^4 whereof is connected by wire 23 with the coil 15' of the magnet G', the opposite end of which is connected 110 by wire 24 with the junction-point 17. From said junction-point 17 the main circuit continues through the transmitter F'' , which is wired exactly like the transmitter F' described, and the transmitter F^3 , likewise wired in general like the transmitters described, to the junction-point 17', whence the circuit is completed by wire 25 to the ground and by wire 26 from the ground to the negative terminal 115 of the generator H. The supervisory branch of the box F' is normally closed through contacts c^6 normally maintained in closed relation, while the float c' is depending by an insulated block c^7 , carried by the lever c^4 , but adapted to be laterally moved by the eleva- 120

tion of the float c' and a consequent vibration of lever c^4 to open-circuit position. The supervisory circuit of the box F^3 is normally closed through the mercury of thermometer 5 by wires inserted therein at the point approximating freezing-point being included in said branch. An additional wire 27 is preferably run from the upper, or boiling-point contact of the thermometer, to the main branch 10 of the circuit.

At the central station suitable apparatus may be required for indicating and recording signals, in the drawings the relay 11 being provided with an armature 28, included in a 15 normally open circuit 29, containing the recording device 30 and a local battery 31, said local battery being adapted to be closed by the retraction of the armature 28 upon the rupture of the main circuit. If a reduction 20 of pressure occurs in the riser A sufficient to be disadvantageous to the extinguisher system and sufficient to enable water to flow through the valve B, the closer coiling of the loop of the elastic tube d , attendant upon the 25 reduction of pressure, causes the supervisory branch of the circuit of box F' to be broken by the withdrawal of point d^4 from the mercury contact. Now current from the generator is all caused to pass from the main branch 30 of the box F' , so that only the coils 14 and 15 of the magnet G' are energized and the magnet thereby unbalanced. Consequently it attracts its armature, which has been normally standing unattracted, thereby releasing the 35 transmitting-wheels, thus tripping the box, for one round of operation. It will be seen that since the supervisory circuit, including therein the pen and contact 19 and 20, respectively, is broken the signal transmitted to 40 central station will be characteristic of the elevated portions of the number-wheel f' , the number-wheel f^2 being electrically inactive. Should, however, the pressure conditions in 45 the riser be promptly restored to normal and the loop of the pressure-indicator be expanded to again immerse the contact d^4 in the mercury contact d^3 , to reestablish the circuit conditions originally described and a second time thereby 50 trip the transmitter-box for a round of operation the continuity of the two branches of the circuit will be alternately broken by the raised continuous peripheral portions of the respective wheels, so that each wheel is able to send a series of impulses characteristic of a number, 55 thereby producing at the central station a signal distinguishable from that sent by the pressure reduction. In this manner the central office will be apprised, first, of the abnormal condition in the sprinkler system, and, second 60 or later, by a characteristic distinguishable signal upon the restoration of normal conditions. The action as regards the water-level indicator is substantially the same, the rise of water-level above the valve B so as to fill 65 the chamber c causing the elevation of the

float c' , the movement of lever c^4 in its fulcrum-diaphragm, and the rupture of the supervisory circuit of box f^2 at the contact c^6 . By this means "water-columning" or leakage of water above the variable-pressure valve in 70 the riser may be detected, or, in case of a pressure-tank, by raising the float c' to open the supervisory circuit as the water-level drops, the drop of the water in such a device may be detected. Should, however, water-columning occur, it is important to know the temperature of the water that it may be prevented from freezing until steps are taken to remove the difficulty in the system. This is 75 provided for by the temperature-indicating arrangement E, for if the temperature of the water falls below a predetermined point the supervisory circuit of box F^3 is broken, tripping said box by unbalancing its relay G^3 and causing it to send in a trouble-signal. 80 Should the temperature of the water, on the other hand, rise dangerously close to boiling-point, contact is made by the mercury in thermometer E with the wire 27, so that a short circuit is established thereby around 85 the coils of the magnet G^3 included in the main branch, thereby unbalancing the magnet and tripping the box. Thus complete supervision over these features of possible trouble in a sprinkler system is accomplished 90 in such a way that the supervising officials are notified of the occurrence of trouble, the signals transmitted upon the occurrence of each different trouble being distinguishable, and the signals being distinguishable as to 95 box-number, and the signals transmitted upon the restoration of normal conditions being distinguishable from those sent upon the occurrence of the trouble. Furthermore, it is 100 to be noted that by the arrangement herein described, we enable the supervising officials to distinguish between such conditions in the system as show mere "trouble" and such conditions as occur in the event of "fire" and the consequent complete operation of the 105 sprinkler system. It will be understood that in the event of fire, and the opening of the sprinkler-heads of the system, the pressure within the riser A immediately falls, causing the 110 pressure-indicator to send its trouble-alarm, and the water commences to flow through the pipe d , so that it fills almost instantly: the pressure is restored above that normally existing in the dry-pipe portions of the system, 115 thereby causing the pressure-indicator to again trip its box to send the restoration signal, while the flow of water, filling the chamber c and elevating the float c' causes the water-level box F^2 to send its trouble-signal. If desired, the boxes may be so timed 120 in operation that they do not conflict, although in many instances special precaution in this regard is not necessary. It will be apparent, however, that the sequence of signals described is indicative of a sequence of 125 130

conditions in the sprinkler system which only occur in the natural course of events in case of fire or such an opening of the sprinkler-head as would ordinarily be occasioned 5 only by fire. Therefore the devices of the system operate in the manner of a fire-alarm, as well as to afford complete supervision of the associated parts of the fire-extinguisher apparatus.

- 10 For the purpose of notifying local attendants of abnormal pressure or liquid-level conditions, as by automatically ringing an alarm-bell, we provide a bell K, located local to the protected area, a battery k', contacts k² and k³ normally open, adapted to be closed by the lateral movement of the lever c⁴, as when water enters the chamber c and raises the float c⁵, and other contacts k⁵ and k⁶, normally open and adapted to be closed upon the decrease of 20 pressure below normal, the two sets of contacts being placed in parallel with reference to each other, as shown, so that the closing of either pair will cause the bell to be rung.

While we have herein described in some detail an embodiment of our invention which we find to be highly advantageous in its application, we do not desire to be understood as limiting ourselves to the specific construction and connections herein shown and described further than as specified in the claims.

Having thus described our invention, what we claim, and desire to secure by Letters Patent of the United States, is—

1. In combination with a receptacle of a fire-extinguisher system wherein the conditions of pressure and liquid-level change when the system is active, a pressure-indicator, a water-level indicator, means associated with said indicators for giving distinguishable signals 35 upon the variations of conditions of pressure and water-level.

2. In combination with a receptacle of a fire-extinguisher system wherein conditions of pressure and liquid-level change when the system is active, of a pressure-indicator and a liquid-level indicator associated with said receptacle, means associated with said devices for giving distinguishable signals upon the variation of conditions of pressure and liquid-level, means located at a supervisory station 45 responsive to said signal, and suitable circuit connections for said signal transmitting and receiving means.

3. In combination with a receptacle of a fire-extinguisher system wherein conditions of pressure and liquid-level change when the system is active, a pressure-indicator, a means for indicating the commencement of liquid-flow, means associated with said indicators for transmitting distinguishable signals upon the suitable actuation of said indicating means, signal-responsive apparatus, and normally closed circuit connections between said signal-transmitting means and the signal-re-

sponsive devices, including a source of current-supply, whereby the signaling system is maintained under test.

4. In combination with a receptacle of a fire-extinguisher system, wherein upon the commencement of activity of the system a pressure variation and commencement of liquid-flow occurs sequentially, means associated with said receptacle for indicating the pressure variation and commencement of liquid-flow, and signaling means associated with said indicating devices for designating the sequential commencement of pressure variations and liquid-flow in the receptacle.

5. In combination with a receptacle of a fire-extinguisher system wherein upon the commencement of activity of the system a pressure variation and commencement of liquid-flow occurs sequentially, means associated with said receptacle for indicating the pressure variation and commencement of liquid-flow, and signaling means associated with said indicating devices for designating by distinguishable signals the sequential commencement of pressure variations and liquid-flow in the receptacle.

6. In combination with a receptacle of a fire-extinguisher system wherein variation in pressure and commencement of liquid-flow are sequential upon the commencement of activity of the system, means associated with said receptacle for indicating the variation in pressure and succeeding commencement of liquid-flow, electrical signal-transmitting means associated with said indicators, and adapted to transmit a distinguishable signal upon the actuation of each of said indicating means, a supervisory station equipped with a signal-receiving apparatus, and suitable circuit connections between said signal-transmitting and signal-receiving apparatus, including a means of current-supply.

7. In combination with a receptacle of a fire-extinguisher apparatus wherein variation of pressure and flow of liquid commence sequentially when the system becomes active, a pressure-indicator associated with said receptacle, a means for indicating the commencement of water-flow associated with said receptacle, said pressure-indicator and water-flow indicator being arranged to act successively upon the commencement of activity in the receptacle, a transmitter associated with each of said indicators, adapted to transmit a signal, a signal-receiving apparatus and suitable circuit connections between the signal transmitting and receiving apparatus.

8. In combination with a receptacle of a fire-extinguisher system wherein variations of pressure and commencement of water-flow practically occur sequentially, means for indicating commencement of water-flow, a pressure-indicator, a means associated with each of said devices for transmitting a given signal upon the actuation of its indicator to indicate

abnormal conditions in the receptacle, and another signal upon the restoration of normal conditions, signal - receiving apparatus and suitable circuit connections between the signal-transmitting means and signal-receiving apparatus.

9. In combination with a receptacle of a fire-extinguisher system wherein variations of pressure and commencement of water-flow practically occur sequentially, means for indicating commencement of water-flow, a pressure-indicator, a means associated with each of said devices for transmitting a given signal upon the actuation of its indicator to indicate abnormal conditions in the receptacle, and another signal upon the restoration of normal conditions, said two signal-transmitting means adapted to transmit signals of distinguishable character from each other, signal-receiving apparatus and suitable circuit connections between the signal-transmitting means and signal-receiving apparatus.

10. In combination with a receptacle of a fire-extinguisher system wherein predetermined liquid-level and pressure conditions should be normally maintained, a pressure-indicator, a water-level indicator, and a temperature-indicator associated with said receptacle, signal-transmitting means associated with said indicators for transmitting distinguishable signals upon the actuation of said indicators, to show predetermined degrees of abnormal conditions in said receptacle, signal-responsive means and suitable circuit connections between the signal-transmitting and signal-responsive means.

11. In combination with a fire-extinguisher system wherein predetermined conditions of pressure and water-level should be normally maintained, a pressure-indicator, a water-level indicator, a temperature-indicator, a separate transmitter associated with each of said indicators for control thereby, signal-receiving apparatus and suitable circuit connec-

tions between said signal-receiving apparatus 45 and said signal-transmitter.

12. In combination with a fire-extinguishing system wherein certain conditions of pressure, water-level and temperature should be normally maintained, means for indicating 50 conditions of pressure, water-level and temperature associated with said system, an independent signal-transmitter controlled by each of said indicating means, a signal-receiving apparatus, and a single main-line circuit including said signal-transmitting apparatus and signal-receiving apparatus.

13. In combination with a receptacle of a fire-extinguisher system wherein the conditions of pressure and liquid-level change when 60 the system is active, of a pressure-indicator, a water-level indicator, means associated with said indicators for closing an electric circuit upon the variation of conditions of pressure or liquid-level, an electric circuit, a source of 65 current for said circuit and an alarm device in said circuit.

14. In combination with a fire-extinguisher system comprising fluid-retaining means wherein the conditions of pressure and liquid-level change when the system is active, means associated with said fluid-retaining means for indicating the pressure variation and the commencement of liquid-flow, and means associated with said indicating means for giving 75 distinguishable signals upon the actuation of said indicating means to indicate the variation of conditions of pressure and liquid-level in the fluid-retaining means.

In testimony that we claim the foregoing as 8c our own we affix our signatures in presence of two witnesses.

JAMES G. NOLEN.
